COVER FOR TEMPORARY BINDERS AND
METHOD OF MAKING THE SAME

Clarence D. Trussell, Poughkeepsie, N. Y., assignor to Trussell Manufacturing Company, Poughkeepsie, N. Y., a corporation of New York

Application March 8, 1935, Serial No. 9,918

8 Claims. (Cl. 129—24)

This invention relates to improvements in the manufacture of book covers, and more particularly to an improved form of cover for a temporary, or loose-leaf, binder of the type in which 5 the leaves are impaled upon rings or other fastening devices.

In general, books of the type above referred to include three essential parts, namely, a cover, a backing plate, and a ring, or other form of leaf binding mechanism. In the manufacture of such 10 books it has been the practice to form the cover and backing plate as one unit; and then to attach the binding mechanism to the backing plate. When the covers of such books are made of several 15 plies of material, or of thick leather which may be split, relatively little trouble is encountered in securing the backing plate to the cover. However, when the cover is made of thin leather, or of a single-ply leather substitute, then the 20 problem of attaching the ring mechanism becomes more difficult. One method of solving this difficulty is shown in Patent No. 1,802,794, wherein the cover is grasped between the backing plate and the binding mechanism. In this form the 25 exposed metal backing plate has been objected to as unsightly, and further, as constituting a menace to the highly polished surface of a desk or table on which the book rests.

An object of the invention is to provide a book 30 cover made of single-ply material, or thin leather, in which no metal parts protrude through the cover.

Another object of the invention is to provide a book cover which may be fabricated without including either the backing plate or the binding 35 mechanism, whereby such covers may be conveniently stacked in flat form to await their use.

A further object of the invention is to provide a single-ply cover which may be used with a spurred backing plate of the type shown in Patent 40 No. 1,790,779.

Other objects, and various features, of the invention will be made apparent in the following description, which is to be read in connection with 45 the accompanying drawing, in which

Figure 1 is a fragmentary perspective view of the inside of a binder incorporating the principles of my invention;

Fig. 2 is a fragmentary perspective view of the 50 outside of the binder of Fig. 1;

Fig. 3 is a sectional view taken on the line 3—3 of Fig. 1 showing a ring mechanism in dotted lines;

Fig. 4 is a plan view of the binding strip of Fig. 51 1, and

Fig. 5 is a sectional view of the binding strip shown in Fig. 4.

In the drawing, similar designations referring to similar parts, numeral 10 designates a book cover, of which 11 is the back, and 12, 12 are the sides. Preferably the back and sides are formed from one piece of thin leather, or of single-ply fabric. The outer surface of the cover is embossed, or printed, with a number of lines 13, one purpose of which is to improve the appearance of 10 the book. While the exact positioning of the lines is a matter of taste, it is important that longitudinal lines 13a should substantially define the junction between the sides 12 and back 11; that longitudinal lines 13b should be relatively close to lines 15 13a, the distance varying with the size of the binder; and that transverse lines 13c should be relatively close to the top and bottom edges of cover. Since the material is quite thin, it is apparent that these lines will also appear on the 20 inside of the cover, as is shown in Fig. 1. Using the lines 13a, 13b as guides, two metal stays 14 may be cemented as at 15 to the inside of the cover. (See Figs. 1 and 3.) These stays, as 25 will later appear, are for the purpose of protecting the book against indentation, and consequent wear, by the rings or other binding mechanism. A binding strip 16, composed of a piece of single-ply material having a central slit 17 therein, is then superimposed upon the inside of the cover 10, this strip being of sufficient size to cover the area bounded by lines 13b and 13c. Dabs of 30 paste at the corners of the binding strip may be utilized as a means for temporarily holding the strip in this position. The cover is then turned over, and using the lines 13a, 13b and 13c as guides (see Figs. 1, 2 and 3) the binding strip 16 is 35 stitched firmly in place. Thus, as is seen in Fig. 3, the stays are held not only by the cement 15, but also by the pocket formed between the cover and the binding strip; and further, the binding strip is properly secured to the cover. It is apparent from the foregoing that the lines 13 generally serve not only as a means for improving the 40 appearance of the cover, but also, and more important, that some of these lines, 13a, 13b and 13c, for example, serve as guides whereby the stays and binding strip may be properly positioned on the inside of the cover, and the binding strip 45 stitched in place from the outside thereof. If desired, the covers may now be piled flat and stored until such time as it is desirable to insert the backing plate, and to attach the binding mechanism in the manner hereinafter described. 50 The backing plate 18 (see Figs. 1 and 3) may 55

be composed of a strip of fairly heavy metal, rounded to a desired curvature and stamped to form a plurality of sharp spurs 19 upturned along one or more lines displaced from the center line of the backing plate; and further stamped to provide the tongues 20, which will later be used to clamp the binding mechanism in place. Preferably, the plate 18 is slightly shorter than the back 11 (Fig. 1). Generally, the spurs 19 and tongues 20 are formed in a single stamping operation. The spurs 19, preferably, are slightly inclined toward the center of the backing plate, for a purpose which will appear hereinafter. The backing plate, as a whole, is now inserted in the binder through the slit 17. The binder is then placed in a suitable press and force is applied, whereupon the spurs cut into the binding strip 16 and are bent over towards the center line of the backing plate. The bending of the spurs toward the center of the plate 18 creates a tensional force along the binding strip 16, and consequently draws the back 11 of cover 10 snugly over the convex surface of backing plate 18. For a more detailed description of the backing plate, the method of using it, and the particular features thereof, see Patent No. 1,790,779.

The binding mechanism 21, indicated in dotted lines in Fig. 3, may be of any well known form. As here shown, the mechanism includes a pair of oppositely disposed half rings 22, suitably attached to the ring plates 23. The ring plates are held under the compressive force of a spring plate 24 whereby the half rings 22 are maintained either in closed, or in open, position, in a manner well known to the art. A cover plate 25 serves to improve the appearance of the binding mechanism as a whole. The binding mechanism 21 is attached to the cover by placing it over the backing plate and turning down the tongues 20 in the usual manner.

Referring again to the binding strip 16, it is apparent that the slit 17 could extend throughout the entire length thereof, thus dividing it into two pieces. While such construction could be used, more labor would be required to secure the strips to the cover, a part of its strength would be sacrificed, and the resulting broken edges would be unsightly. In the preferred construction the strip 16 is made of a length substantially equal to the length of the back 11; and the slit 17 is made of a length substantially equal to the length of the backing plate 18. A strip of the preferred form, when stitched as shown in Fig. 1, forms a pocket which is substantially equal to the width of plate 18. However, the length of the pocket is somewhat greater than the length of the backing plate. This additional length, while not absolutely essential, simplifies the problem of inserting the backing plate into the pocket by allowing a longitudinal movement of the plate in the pocket during the insertion process. The unbroken edges of the strip, of course, lend a neat, and, hence attractive, appearance to the ends of the binder.

Stays 14, as hereinbefore mentioned, are designed to protect the cover from indentation by the rings 22. Hence, the exact positioning of these stays will depend upon the size of the back, and the size of the rings. While it has hereinbefore been stated that the stays are cemented to the cover, it is apparent that they might be secured to the binding strip prior to its attachment to the cover. Cementing, either in one place, or the other, is desirable because it prevents rela-

tive movement of the cover and stays, and hence, wear.

It is apparent from the foregoing description that this invention provides a construction which permits the use of a single-ply cover, without having any protuberances on the outside thereof; that it provides a cover which is particularly advantageous because it may be completely made up without including the backing plate, or the binding device; and that it provides a cover, made of single-ply material, or thin leather, which may be used in conjunction with a spurred type backing plate.

While the invention is particularly useful with single-ply covers, it is readily apparent that the same principle may be applied in manufacturing covers of thicker material; and whereas the drawing shows a preferred form of the invention, it is apparent that certain changes may be made therein without in any way departing from the scope of the invention as limited by the appended claims.

What is claimed is:

1. In a temporary binder a cover having side portions and a back, a binding strip secured to the inside of said cover over the back thereof, a slit in said binding strip formed along the center line of the back, said binding strip and said cover forming a pocket into which a backing plate may be inserted through said slit.

2. In a temporary binder a cover having side portions and a back, a binding strip secured to the inside of said cover over the back thereof, a slit in said binding strip of a length less than the length of the back, said binding strip and said cover forming a pocket into which a backing plate may be inserted through said slit.

3. The combination with a binder cover, comprising back and side portions, of a strip of binding material disposed lengthwise of the inner surface of the back portion of the cover and secured thereto along its margins, the binding strip having a longitudinal slit therein and an unsecured portion extending along the sides and ends of the slit, the length of the slit and the dimensions of the underlying pocket between the central portion of the binding strip and the cover back being such as to permit a backing plate for a metal binder mechanism to be inserted through the slit of the secured binding strip and into the pocket.

4. The method of assembling a cover for a temporary binder with a back plate, a pair of stays, and a slotted binding strip for said plate and stays which consists in applying to said cover guide marks visible at its interior as well as at its exterior surfaces, securing the stays to the interior surfaces of said cover in locations determined by the positions of said marks, temporarily attaching the binding strip to the interior of the back portion of the cover in a location determined by the positions of said marks, and with its marginal portions overlying the stays, permanently securing the binding strip to the cover by marginal stitching applied with the outer surface of the cover uppermost, using the marks as guides, inserting the back plate through the slit in the binding strip into the pocket between the binding strip and the cover back, and securing the portion of the binding strip along opposite sides of the slit to the underlying back plate.

5. The method of assembling a cover for a temporary binder with a back plate and a slotted binding strip for said plate, which consists in

5 applying to said cover guide marks visible at its interior as well as at its exterior surfaces, temporarily attaching the binding strip to the interior of the back portion of the cover in a location determined by the positions of said marks, permanently securing the binding strip to the cover by marginal stitching applied with the outer surface of the cover uppermost, using the marks as guides, inserting the back plate through 10 the slit in the binding strip into the pocket between the binding strip and the cover back, and securing the portion of the binding strip along opposite sides of the slit to the underlying back plate.

15 6. The method of making a covering for a temporary binder which consists in forming a plurality of lines which appear both on the outside and inside of the cover material, positioning a slitted binding strip on the inside of said cover 20 material using said lines as guides, stitching said binding strip to said cover material from the outside thereof using said lines as guides, and inserting a backing plate into the pocket formed between the cover material and binding strip 25 through the slit in the binding strip.

7. The method of making a covering for a temporary binder which consists in forming a plurality of lines appearing both on the inside and

outside of a cover, positioning a pair of stays on said cover using the lines as guides, positioning a longitudinally slitted binding strip on the inside of said cover over said stays, stitching the binding strip to said cover from the outside thereof using said lines as guides, said stitching being made on both sides of each of said stays and along both the top and bottom edges of said cover, and inserting a backing plate in the pocket formed between the cover and binding strip 10 through the longitudinal slit formed in the binding strip.

8. The method of making a book cover using a single-ply material, which consists in imprinting a plurality of lines on the cover material which lines appear both on the inside and outside thereof, positioning a slitted binding strip on the inside of said cover material using said lines as guides, stitching the binding strip to the cover material from the outside thereof using 15 said lines as guides, inserting a backing plate into the pocket formed between the cover material and binding strip through the slit formed in the binding strip, and securing the backing plate to the binding strip by means of a plurality of spurs 20 formed on the backing plate.

CLARENCE D. TRUSSELL.
